PORTABLE PROJECTOR

Nolan K. Rhoades, Beloit, and Arthur R. Schmidt, Madison, Wis., assignors to ESB Incorporated, a corporation of Delaware

Filed Feb. 4, 1969, Ser. No. 15,621

Term of patent 14 years

Int. Cl. D16

U.S. Cl. D61- 1

Fig. 1

Fig. 2

Fig. 3

*Fig. 4**Fig. 5**Fig. 6*

FIG. 1 is a perspective view of the portable projector showing our new design;

FIG. 2 is a plan view looking downwardly at the top thereof;

FIG. 3 is an elevational view of one side thereof, the other side (not shown) being identical;

FIG. 4 is a plan view looking upwardly at the bottom thereof;

FIG. 5 is an elevational view of the front thereof; and

FIG. 6 is an elevational view of the rear of the portable projector.

We claim:

The ornamental design for a portable projector, as shown and described.
